CONTROL VALVE MECHANISM FOR
MATERIAL TANKS

James Macdonald Mitchell, Old Lyme, Conn.

Application July 14, 1934, Serial No. 735,271

16 Claims. (Cl. 210—51)

This invention relates to tanks or containers adapted to receive materials of different density having a valved port controlling the feed to or the discharge of materials from the tank. The object of the invention is to provide control mechanism for the port valve dependent in operation upon the accumulation of heavier materials which settle downwardly in the tank, and it is the purpose of the invention to provide mechanism of such character which is relatively simple but extremely efficient in operation.

While not necessarily limited to any particular purpose, the proposed control mechanism is particularly adapted to use in apparatus for settling solid materials out of liquids. The arrangement proposed is such that it may be employed in the settling of various grades of materials, and it is particularly useful in settling apparatus used in the recovery of fine materials.

According to the invention a member is mounted in the tank for movement in a definite path and so arranged that the accumulation of heavier materials in the bottom of the tank impedes or stops the movement of the member. Actuating means is provided to move the member in its path which becomes inoperative when movement of the member is resisted by the accumulation of the heavier materials. Retardation or stoppage of the member acts through suitable mechanism to actuate the material port valve, which in the case of a settling apparatus will be located in the bottom portion of the tank and serve to discharge the accumulation of settled materials.

The member in the tank whose movement is affected by the accumulation of settled materials may be considered as the control mechanism responsible for the actuation of the port valve. However, in certain embodiments of the invention, as will hereafter become apparent, the member retardable by the settled materials may function primarily as a brake or stop mechanism for other mechanism located outside of the tank, in which case retardation or stoppage of the latter mechanism will be employed to control the tank port valve.

The member mounted for movement in a path in the tank to be acted upon by the accumulation of materials therein and the actuating mechanism therefor may take a variety of forms, and the actuating mechanism immediately operating the tank valve will be dependent in construction upon the specific arrangement adopted. In some cases the valve actuating mechanism may be operated directly from the movable member in the tank, while in other instances the valve operat-

ing mechanism will be controlled through the actuating mechanism which moves the tank member through its path. I have in the accompanying drawings illustrated one embodiment of the invention together with certain collateral features thereof, but it will be understood that I do not limit myself to the specific construction and arrangement of parts therein shown.

In the drawings:

Fig. 1 is a view in vertical section of a settling apparatus with one form of my invention applied thereto;

Fig. 2 is a view of the same apparatus taken at right angles to the view of Figure 1;

Fig. 3 is a top plan view;

Figs. 4 and 5 are alternative arrangements providing additional features of construction which may be employed in connection with the assembly of Figures 1 to 3 as auxiliary control mechanism, and which may also be used in substitution for certain operative parts of such assembly.

The tank or container 10 may be of any desired shape and size. The particular form shown is intended as a settling tank, in which case the material port valve, 11, 12, whose operation is controlled by the inventive structure, will be positioned at the lower end of the tank and serve to discharge solid materials from liquid in which they are carried in suspension into the tank through the inlet 13.

The tank valve and mounting therefor is unimportant, as various arrangements may be resorted to in connection with the novel control mechanism to be described. In the embodiment illustrated the valve 12 is supported on a pivoted counter-balanced arm 14 actuatable through an arm 15. The control mechanism may be connected mechanically with the arm 15, but I now prefer to arrange the control mechanism to operate through an electrical circuit and a solenoid 16.

The novel control mechanism includes a member 17 mounted for movement in the tank in a fixed path and so arranged as to be retarded in its movement by settled materials as the level thereof rises in the tank. Means are provided to move the member through its path and arrangement is made whereby the retardation of the member is caused either directly or indirectly to actuate the port valve 12. The member 17 may conveniently take the form of a pivotally supported arm. In the form shown the same is suspended in a vertical position in the tank from a supporting bar 18. In order that the member 17 be effectually acted upon by the settled ma-

terials the same should take the form of a paddle, or at least as is shown include a portion 19 presenting an appreciable surface to be impinged upon by the settled materials.

5 The member 17 will be moved or oscillated through a reciprocatory path by actuating mechanism, and as the level of settled material rises in the tank the movement of the member will be impeded or obstructed. Of course, a variety of 10 different devices may be employed to effect the desired reciprocation of member 17 and so arranged as to become inoperative when movement of the member is obstructed by the settled materials. In the embodiment of the invention 15 shown the actuating mechanism constitutes a balanced receiver 20 pivotally supported at point 21 above the tank by a suitable bracket 22. Such balanced receiver is a substantially conventional diamond box having opposing compartments to 20 which liquid is supplied from a pipe 23. The liquid supply pipe is arranged in operative position above the receiver 20 so that one compartment fills, tips the receiver to bring the other compartment under the supply pipe and dis- 25 charges conveniently into the tank. The other compartment in turn is filled to tip the receiver and then discharge, and the cycle is continuously repeated to produce in the receiver an oscillatory movement. Buffers 24 may be provided 30 to stop the movement at each end of its path. By providing a valve in the supply pipe 23 the period required to fill the compartments of the balanced receiver 20 may be regulated at will and the oscillatory movement thereof adjustably deter- 35 mined.

The reciprocating member 17 has an upward extension and is connected to the diamond box through a pin 25 so as to be rocked back and forth as the diamond box oscillates. The path of 40 movement of the active portion 19 of the arm 17 will be determined by the length of the arm and the relative positions of its pivot support 18 and its point of connection with the actuating mechanism just described. It will be evident that as 45 the settled materials rise in the tank they will close in on the active portion of the reciprocating member 17 to restrict the same in its path of movement and in most cases completely stop the same. Since the diamond box employed to actuate the member is weight-operated through the liquid received from the supply pipe 23, the connection 25 of the member with the diamond box 20 will cause movement of the latter to be retarded or stopped. It will therefore be evident 50 that the retardation in movement of the member 17 may directly be employed to operate the port valve or, alternatively, the cessation in movement of the actuating mechanism, the diamond box, may similarly be used. The latter arrange- 55 ment is used in the embodiment of the drawings, arrangement being made whereby stoppage of the diamond box will cause liquid to be discharged therefrom, such discharge in turn operating through suitable mechanism to actuate the port 60 valve 12.

The arrangement just mentioned may be carried out as best shown in Figs. 2 and 3. The corresponding compartments 26 and 27 of the diamond box are provided with similar overflow outlets 28 and 29, so located as to be above the normal level of liquid when one of the compartments has become sufficiently filled to tilt the diamond box. Since some lapse of time is required to fill one compartment of the diamond box, it will be 75 evident that the oscillatory movement thereof

and hence the reciprocatory movement of the member 17 is intermittent. Thus, the settled materials accumulating in the bottom of the tank will gradually build up to a point where, while one of the compartments is being filled, movement of the member 17 and of the diamond box will be obstructed. Under such conditions, the compartment of the box under the liquid supply pipe will continue to fill and cause the discharge of liquid through one of the outlet pipes 28 or 29. 10

Adjacent the diamond box is mounted a balanced arm 30 pivotally supported on the bracket 22. Such arm is provided with a receptacle 31 operatively positioned to receive the discharge from one of the diamond box compartments under the conditions just mentioned. Such receptacle as it becomes filled will cause the member 30 to swing on its pivot. On the opposing arm of the member 30 is located a mercury switch 32 which will be closed as the receptacle 31 swings the member on its pivot. The switch 32 is located in the supply line for the solenoid 16, and as the circuit is closed the solenoid will be energized to operate the tank discharge valve 12. 25

When the valve 12 is opened the accumulated settled materials will be discharged. A small outlet 33 is provided in the receptacle 31 to discharge the liquid therefrom and allow the arm 30 to swing back and open the solenoid switch 32. 30 The valve 12 will then close, and since the discharge of settled material frees the reciprocating arm 17, such arm together with the diamond box actuating mechanism will be again ready for operation. 35

It will be appreciated that the intermittent operation of the control member 17 which is actuated upon by the settled materials is desirable in a settling tank. Particularly where the same is employed for the settling of fine materials, the intermittent actuation is of great advantage in that continuous operation of the member 17 would keep the liquid in the tank so stirred up as to retard the settling of the lighter materials. The speed of movement of the member 17 may, as 40 above indicated, be adjustably controlled by regulating the flow of liquid to the diamond box 20. The size of the diamond box can also be varied so as to increase or decrease the time each compartment requires to be filled, and of course the period required for filling will determine the length of time the reciprocating member 17 is at rest at each end of its path of movement. 45

If difficulty is encountered in the arrangement described due to stopping of the member 17 at an intermediate portion of its path so as to prevent liquid from the diamond box compartments being discharged into the receptacle 31, it may be desirable to provide a plurality of discharge valves and separate control mechanisms therefor at different portions of the tank. However, positive measures may be taken to overcome the difficulty by providing other mechanism incorporating a time control means which will become operative when the reciprocating member 17 has been stopped for a designated time period, no matter what position in its path the member 17 occupies when the accumulated materials fill in to block the same. 60

Several possible arrangements operative independent of the point of stoppage of the member 17 are shown in Figures 4 and 5, the same being shown as applied to a construction wherein the actuating mechanism for the member 17 constitutes the diamond box 20. In such arrange- 70 75

ments a supply circuit to the solenoid 16 will include a series of switches which will be simultaneously closed when the reciprocating member 17 is at intermediate portions of its path of movement. Included in the circuit will be a time relay so arranged that if the reciprocating member is stopped by the accumulated materials the several switches will close, and after a short interval the time relay will operate to complete the circuit, 10 energize the solenoid and open the port valve 12.

As applied to the diamond box actuating mechanism previously described, the solenoid circuit will include a pair of switches 34 and 35 arranged in a circuit with a time relay 36, all as shown in 15 Figure 4. Such switches will be mounted on freely swinging pendulums 37 and 38 pivotally supported at the opposing ends of the diamond box 20. When either end of the diamond box is up for the filling of a compartment with liquid, 20 the corresponding switch will be held horizontal by its pendulum support, and both of the switches will be maintained horizontal during movement of the diamond box through its oscillatory path. As long as the switches are maintained horizontal 25 the portion of the circuit between them will be maintained closed, but the solenoid circuit will not be completed until the time relay 36 becomes operative. Hence, the quick movement of the diamond box from one end of its path to 30 the other is not effective to complete the circuit, and it is only when the accumulation of settled material stops the box at an intermediate point that the time relay will become effective in co-operation with the pendulum switches to energize 35 the solenoid and open the tank port valve. During the time interval when the diamond box is at one or the other end of its path for the filling of one of its compartments arrangement is made to tilt one of the switches 34 or 35 so that the 40 circuit will not be closed even though the time relay should become operative. In Figure 4 members 39 and 40 are provided in association with the end stops to alternately engage the pendulum supports 37 and 38 to tilt the switches and therefore 45 by insure an open circuit during the filling of each diamond box compartment. Of course, it is only necessary to open one of the switches 34 and 35 at each end of the diamond box path and it is immaterial which one is opened during the 50 filling of the right and the filling of the left compartments of the box.

In the arrangement of Figure 5 a further and somewhat simplified arrangement is shown. In this case stationary switches 41 and 42 are substituted for the pendulum switches 34 and 35 carried by the diamond box in Figure 4. Such switches are of the lever actuated type having arms 43 and 44 adapted to be depressed by the diamond box to open the solenoid circuit as the 55 diamond box reaches first one end and then the other of its oscillatory path. To engage the respective switch arms 43 and 44 coating pins 45 and 46 may be associated with the ends of the box. Either of the arrangements just described 60 may be employed in an auxiliary control circuit additional to the main actuating mechanism comprising elements 30 through 33 of the embodiment of the invention shown in Figure 2. It will be evident, however, that the arrangements of 65 Figure 4 or 5 may be used alone as the main control circuit for the valve solenoid.

Since the invention may be applied to a variety of uses and the essential features thereof embodied in forms differing from the details of 70 construction herein illustrated and described, it

will be understood that the scope of the invention is to be determined in the light of the accompanying claims.

I claim:

1. In a settling tank, a valved discharge for settled materials, a member movable intermittently in a fixed path in the tank and arranged to have its movement arrested by settled materials as the level thereof rises in the tank, periodically operative actuating means to move the member through its path, and means rendered operable by the stopping of the movable member to open the valved discharge. 5

2. In a settling tank, a valved discharge for settled materials, a member mounted for reciprocatory movement in the tank and arranged to be stopped from movement by the building up of settled materials, actuating means to reciprocate said member, and means operable through stoppage of the member to open the valved discharge. 15

3. In a settling tank, a valved discharge for settled materials, an oscillating arm in the tank arranged to be rendered inoperative by settled materials as the level thereof rises in the tank, 25 and means becoming operative through the stopping of said arm to open the valved discharge. 20

4. In a settling tank, a valved discharge for settled materials, an arm mounted for reciprocatory movement in the tank and arranged to have 30 its movement impeded by materials settled in the tank, means to reciprocate said arm, and means operable as the level of settled materials rises in the tank to impede the movement of the arm to open the valved discharge. 35

5. The combination of a fluid container adapted to receive materials of varying density, a valved material port in the container, a member having periodic reciprocatory movement through a fixed path in the container and arranged to be 40 acted upon by heavier materials settling in the bottom of the container, and means operative through obstruction of the periodically reciprocating member to actuate the port valve.

6. In a settling tank, a valved port, a member 45 mounted for reciprocatory movement in the tank through a path in a vertical plane and arranged to have its movement impeded by heavier settled materials as the level thereof rises in the tank, means for moving said member in its path, 50 and means responsive to the obstruction of the movable member by settled materials to operate the port valve.

7. In a tank for receiving materials of varying density, a valved material port, a pivotally 55 mounted reciprocatory arm in the tank arranged to be impeded in its movement by the rise in level in the tank of heavier denser materials, means for reciprocating the arm on its pivot, and means becoming operative through obstruction 60 in movement of the arm to operate the port valve.

8. In a settling tank, a valved discharge for settled materials, a pivotally mounted paddle, means to reciprocate the paddle, said paddle projecting down from its pivot into the tank to be 65 obstructed in its movement by the rise in level of settled materials, and means operable through obstruction of the paddle to operate the valved discharge.

9. In a settling tank, a valved discharge for 70 settled materials, a member movable in a fixed path in the tank and arranged to have its movement obstructed by settled materials as the level thereof rises in the tank, a reciprocatory member connecting with said movable member so as 75

to be stopped from movement when the movable member is obstructed, and means operable through the stopping of the reciprocatory member for operating the discharge valve.

5 10. In a settling tank, a valved discharge, a member mounted for movement in a path in the tank and arranged to be impeded in its movement by settled materials as the level thereof rises in the tank, weight operated means for moving said member in its path, and means operable through retardation in movement of the member to open the valved discharge.

15 11. In combination, a fluid container adapted to receive materials of different density, a valved material port in the container, a balanced oscillating receiver, means for oscillating said receiver, means in the container acted upon by heavier materials settling therein for impeding oscillation of the receiver, and means controlled by the balanced receiver for operating the port valve.

20 12. In a settling tank, a valved discharge, a balanced oscillating receiver, a liquid supply for oscillating the receiver, a reciprocatory member connecting with and actuatable by the receiver arranged to be retarded in its movement by settled materials as the level thereof rises in the tank, and means responsive to retardation in movement of the reciprocatory member to actuate the valved discharge.

25 30 13. In a settling tank, a valved discharge, a balanced oscillating receiver having a pivotal support, compartments in the receiver arranged on opposite sides of the pivotal support, a liquid supply arranged in operative relation to the receiver to feed liquid alternately to the several compartments therein and cause the receiver to oscillate, a reciprocating member in the tank oscillating with the receiver, said member connecting with the receiver and being arranged to be retarded by settled materials as the level thereof rises in the tank to stop oscillation of the receiver, overflow outlets in the compartments of the receiver operative when movement of the receiver is stopped to discharge liquid received

from the liquid source, and means actuatable by the discharge of liquid from the compartment overflow outlets to actuate the tank discharge valve.

5 14. In a settling tank, a valved material port, a member reciprocating in a fixed path in the tank and arranged to be stopped from movement by settled materials as the level thereof rises in the tank, and time controlled means operative when said member is stopped at an intermediate 10 point in its reciprocatory path to actuate the port valve.

15 15. In a settling tank, a valved material port, an oscillating balanced receiver having a pivotal support, compartments in the receiver arranged 15 on opposite sides of the pivotal support, a source of liquid operatively positioned to supply liquid alternately to the several compartments of the receiver to oscillate the same in its path, means in the tank connecting with the receiver and 20 acted upon by settled materials to stop movement of the receiver, outlet means in the several compartments of the receiver arranged to discharge liquid therefrom when the receiver is stopped at certain points in its oscillatory path together 25 with means actuatable by said discharged liquid to operate the tank port valve, and time controlled additional means operative to actuate the tank port valve when the receiver is stopped at intermediate other points in its oscillatory path. 30

16. In a settling tank, a valved discharge for settled materials, an arm extending downwardly into the tank, a horizontal pivot supporting the arm, means for reciprocating the arm to cause its lower portion to swing back and forth across 35 the tank, a paddle secured to and movable with the lower portion of the arm, said paddle being adapted to be obstructed by the rise in settled materials in the tank and operating to stop movement of the arm, and means operative through 40 the stoppage of the arm to open the valved discharge.

JAMES MACDONALD MITCHELL.
